TREATMENT TABLE

Filed Sept. 8, 1924

FIG. 1.

FIG. 2.

FIG. 4.

FIG. 3.

INVENTOR:

MATTHEW R. McBURNEY,

By: Otto D. Kueger,
his Atty.

UNITED STATES PATENT OFFICE.

MATTHEW R. McBURNEY, OF LOS ANGELES, CALIFORNIA.

TREATMENT TABLE.

Application filed September 8, 1924. Serial No. 736,570.

This invention relates to devices used by physicians and the like professionals for treating and readjusting abnormal conditions in the human body; and especially for therapeutic treatments of the organs.

One of the objects of this invention is to provide a device by which a traction operation may be applied to a patient.

Another object is to provide a table with tilting top portions to which a patient can be held to receive traction massages by the tilting and straightening actions of the tiltable tops.

Another object is to provide a device by which a patient can be supported for traction massages.

Another object is to provide adjustments by which patients of different sizes can be treated on such a traction table.

Other objects will appear from the following description and appended claim as well as from the accompanying drawings, in which—

Fig. 1 is a front elevation of traction mechanism tiltably supported on a frame structure, the frame structure being shown in longitudinal vertical section, the front side of the frame having been cut off so that the mechanism may be more clearly observed.

Fig. 2 is a top plan view of a treatment table embodying the invention, having a slightly modified body attachment.

Fig. 3 is a cross-section through one of the table tops showing arm-supports in side elevation.

Fig. 4 is a fragmentary detail front elevation of controlling mechanism for the modified body attachment shown in Fig. 2.

The principal features involved in this invention are the yielding inter-connected top, traction mechanism, and the combination of the yielding top and the traction mechanism.

As illustrated in the drawing in Fig. 1, the treatment table consists mainly of a frame structure 5, a tiltable top 6, and another tiltable top 7. The two tiltable tops 6 and 7 are hingedly inter-connected by link members 8 and 9.

The tiltable top 6 is swingably mounted as indicated at 10 on the frame 5. The tiltable top 7 is swingably mounted as indicated at 11 on the frame 5. By the link inter-

connections 8 and 9, any tilting movement or 55 action of one tiltable top is of necessity transmitted to the other tiltable top.

The link member 8 is illustrated as rigidly connected to the underside of the tiltable top 6, as indicated at 12, the connected end 60 13 together with the free link end of the link member 8 being in form of an integral bar bent and formed to project towards the other tiltable top.

The second link member is hingedly connected as illustrated at 13_a to the free end of the link member 8 at one termination, and is also hingedly connected as indicated at 14 at its other termination to a suitable connection on the under side of the tiltable 70 top 7. Though illustrated as hingedly connected, it must be understood that this yielding interconnection can be made in other similar suitable form, as pivotally or by interengaged loops on the ends of the link members.

By this double pivot connection 13_a and 14, the link members can be moved to the position indicated in dotted lines at 16 when the tiltable tops are moved to the positions 80 indicated in dotted lines at 17 and 18.

A patient disposed on these tiltable tops may receive bending treatments and other treatments practicable on such tilting tops.

A narrow top piece 19 is also provided, 85 having slotted supports 20 by which the top 19 is adjustably mounted on the frame 5 for adjustments in a vertical direction. This top piece may be set as by set-screws at a point indicated at 21 to bring the top 90 surface of the top member 19 at a desired height to serve as a cooperating or counter-acting member in relation to the tilting tops for certain treatments.

A patient treated on the tilting tops, when the tilting tops collapse or tilt to the positions indicated at 17 and 18, may receive counteracting treatments when touching or hitting the comparatively stationary adjusted top member 19.

For automatic and somewhat continuous tilting action, a motor-driven mechanism is mounted within the frame structure 5, so that the tilting top 7 may be tilted up and down through the mechanism. As illustrated, a motor 40 is provided to transmit its rotary motion to the gears 22 through the belt 41. The connecting rod 23 is con-

nected to the larger one of the gears so that the rotary motion of the gears may produce an up and a downward movement of the top 7.

5 To produce a combination of traction treatments together with the above-described treatments, suitable supporting and fastening means are provided on the tilting tops.

To treat a patient with traction massages, 10 a certain part of the body of the patient is preferably held stationary to one of the tilting tops. Upright members 24 are illustrated in Figs. 1, 2, and 3, of a form that may be disposed in the arm-pits of a patient.

15 To make these uprights adjustable so that they may be applied in the arm-pits of patients of different chest widths, the uprights are mounted slidably crosswise to the table top as indicated at 25 in Figs. 1 and 3.

20 When so slidably mounted in relation to the tiltable top 6, these uprights 24 form the comparatively rigid and stationary parts in relation to which other mechanism must be adjusted to fit the different body lengths of 25 different patients. For holding the head of

a patient to the tilting top 6, a brace 26 is provided with a number of hooks 27. A strap 28 is provided of a form that may be applied under the chin of a patient. This 30 strap 28 is provided with a suitable number of links 29 by which the strap may be adjustably attached to the brace 26 in relation to the body supports 24.

35 A waist strap 30 is provided by which the lower extremities of a patient may be held to the second tilting top 7.

In Fig. 1 this waist strap is applied to a brace 31 that is provided on the furthermost end of the tilting top 7.

40 In Figs. 2 and 4 a slightly modified form of waist attachment is illustrated. The waist strap 32 is provided with side straps 33 and 34 that are connected to an adjustable brace 35. The adjustable brace 35 is made in the 45 form of two uprights on opposite sides of the tilting top 7 mounted jointly on a common shaft 36 on the under side of the table top 7. A toothed segment member 37 is provided on one of the uprights by which the 50 inter-connected uprights may be adjusted for lengthwise adjustments of the waist belt

32 in relation to the table tops. The toothed segment member can be held in adjusted position by a pawl 37a.

While a patient is held to the tilting table 55 tops 6 and 7 by the body supports 24, head strap 28, and the waist belt, the patient is bound to receive traction massages on each straightening of the table tops. By adjusting the waist belt in lengthwise direction of 60 the table top by means of the straps 38 of the form illustrated in Fig. 1, or by means of the segment adjustment of the form illustrated in Figs. 2 and 3, the traction massages can be intensified as may be considered necessary or required by the attending physician 65 or the like professional.

It must be understood that the end of the waist-belt is merely in form of a strip or string tied to the member 31, as illustrated in 70 Fig. 1, and that such a strip or string can be of any length to allow a suitable or required lengthening of the lower end of the waist-belt so that the waist-strap 30 may be applied around the middle of any person re- 75 gardless of how tall such a person is.

Having thus described my invention, I claim:

In a treatment table, a top made in sections certain of the sections being swingably 80 mounted for swinging actions in a vertical plane in opposite directions yieldingly connected at adjoining edges in spaced relation, another top section having means for vertical adjustment to form a comparatively 85 stationary part between the opposite swinging parts, supports spaced from the opposite ends of the whole table and from the said adjoining edges, operating means in operative connection with one of the first-named 90 top sections by which the connected top may be tilted alternately with the near ends of the oppositely swinging sections moving simultaneously up and down past the said stationary part, and attaching means firmly 95 mounted on the free swinging ends of the said sections for holding a patient to the swinging parts while partly resting on the said stationary part.

In testimony that I claim the foregoing 100 as my invention I have signed my name.

MATTHEW R. McBURNEY.
